The ornamental design for a door for dishwasher, as shown and described.

DESCRIPTION

FIG. 1 is a front perspective view of the door for dishwasher showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is a partial enlarged view of the area '8' as identified in FIG. 1; and,

FIG. 9 is a perspective view showing the design in state of use.

The broken lines depict portions of the door for dishwasher that form no part of the claimed design. The additional portions of FIG. 9 drawn in broken lines show environmental structure only and form no part of the claimed design. The dot-dashed broken line shown in FIGS. 1 and 8 indicate
